(57) **CLAIM**

We claim the ornamental designs for container with dispensing
closure, as shown and described, except as disclaimed
herein.

DESCRIPTION

FIGS. 1-7 are views of an exemplary container with dispensing closure.

FIG. 1 is an upper perspective view of the container with dispensing closure.

FIG. 2 is a front elevational view of the container with dispensing closure.

FIG. 3 is a rear elevational view of the container with dispensing closure.

FIG. 4 is a right side elevation view of the container with dispensing closure, for which a left side elevational view would be a mirror image.

FIG. 5 is a top plan view of the container with dispensing closure.

FIG. 6 is a bottom plan view of the container with dispensing closure; and,

FIG. 7 is an upper perspective view of the container with dispensing closure, shown with the dispensing closure in the open condition.
